(57) **CLAIM**

The ornamental design for a display screen with transitional graphical user interface, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a display screen with transitional graphical user interface showing a first image in a sequence of transitioning images, according to a first embodiment

FIG. 2 is the display screen with transitional graphical user interface of FIG. 1 showing a second image in a sequence of transitioning images; according to a first embodiment;
FIG. 3 is a display screen with transitional graphical user interface showing a first image in a sequence of transitioning images, according to a second embodiment;

FIG. 4 is the display screen with transitional graphical user interface of FIG. 3 showing a second image in a sequence of transitioning images, according to a second embodiment;
FIG. 5 is a display screen with transitional graphical user interface showing a first image in a sequence of transitioning images, according to a third embodiment;

FIG. 6 is the display screen with transitional graphical user interface of FIG. 5 showing a second image in a sequence of transitioning images, according to a third embodiment;

FIG. 7 is a display screen with transitional graphical user interface showing a first image in a sequence of transitioning images, according to a fourth embodiment;

(Continued)

FIG. 8 is the display screen with transitional graphical user interface of FIG. 7 showing a second image in a sequence of transitioning images, according to a fourth embodiment; FIG. 9 is another view of FIG. 1 but shown without the broken line illustrating portions of the graphical user interface, for clarity of illustrating the claimed design; FIG. 10 is another view of FIG. 2 but shown without the broken line illustrating portions of the graphical user interface, for clarity of illustrating the claimed design; FIG. 11 is another view of FIG. 3 but shown without the broken line illustrating portions of the graphical user interface, for clarity of illustrating the claimed design; FIG. 12 is another view of FIG. 4 but shown without the broken line illustrating portions of the graphical user interface, for clarity of illustrating the claimed design; FIG. 13 is another view of FIG. 5 but shown without the broken line illustrating portions of the graphical user interface, for clarity of illustrating the claimed design; FIG. 14 is another view of FIG. 6 but shown without the broken line illustrating portions of the graphical user interface, for clarity of illustrating the claimed design; FIG. 15 is another view of FIG. 7 but shown without the broken line illustrating portions of the graphical user interface, for clarity of illustrating the claimed design; and, FIG. 16 is another view of FIG. 8 but shown without the broken line illustrating portions of the graphical user interface, for clarity of illustrating the claimed design.

The outermost broken line in each figure illustrates a display screen. The remaining broken lines in the figures illustrate portions of the graphical user interface. None of the broken lines form part of the claimed design.

The appearance of the user interface sequentially transitions between the images shown in FIGS. 1 and 2, FIGS. 3 and 4, FIGS. 5 and 6, and FIGS. 7 and 8. The process or period in which one image transitions to another forms no part of the claimed design.

**1 Claim, 16 Drawing Sheets
